HENRY LA CASSE, OF LOS ANGELES, CALIFORNIA.

PENCIL-SHARPENER.

1,154,325.

Specification of Letters Patent. Patented Sept. 21, 1915.

Application filed December 22, 1913. Serial No. 808,066.

To all whom it may concern:

Be it known that I, HENRY LA CASSE, a citizen of the United States, residing at Los Angeles, in the county of Los Angeles, State 5 of California, have invented new and useful Improvements in Pencil-Sharpener, of which the following is a specification.

This invention relates to a pencil sharpener of the type manipulated in the hands of 10 the user, that is, of the type placed over the end of a pencil and rotated thereon by direct manual operation; and this invention consists in certain combinations and details of structure and operation embodying a peculiar provision and arrangement of cutting edges and embodying the provision in combination of devices for sharpening the leads of pencils.

One of the primary features of my invention 20 is the disposition of the cutting edges effective for sharpening the wooden casing of a pencil. In ordinary pencil sharpeners there is provided a single cutting or knife edge which extends unbroken throughout 25 the length of the cut or sharpened portion of the pencil end. There are various objections to this form of cutting edge, among which is the inability to obtain a good cutting "bite" on the pencil unless excessive 30 pressure is exerted.

One of the primary features of this invention 35 is the placement of the cutting edges at such an angle that a shearing cut is obtained on the pencil and the subdivision of such a cutting edge into a plurality of cutting edges arranged substantially end to end longitudinally on the sharpener, each cutting portion having sharpened end edges so that as the pencil is forced longitudinally 40 into the sharpener each cutting portion will cut a clean shaving from the pencil. In order to obliterate the marks which would otherwise be left by the ends of each cutting portion, the ends of the adjacent cutting 45 portions overhang one another longitudinally in such a manner that at the points of abutment of adjacent cutting portions there are two cutting edges operating upon the same portion of the pencil.

50 All of these features, and other features entering into the combination included in my invention, are explained in detail in the following specification, reference being had to the preferred form of my device shown 55 in the accompanying drawings, in which,

Figure 1 is a view showing a plan of my

improved pencil sharpener in its protective casing, Fig. 2 is an end view thereof, Fig. 3 is an elevation of the pencil sharpener alone, Figs. 4 and 5 are end elevations of 60 the same, Fig. 6 is an exterior view of the protective casing for my pencil sharpener, Fig. 7 is an end view thereof, Fig. 8 is an enlarged longitudinal section of the sharpener, Fig. 9 is a section taken as indicated by 65 line 9—9 of Fig. 8.

In the drawings the numeral 10 may designate a suitable cylindrical casing in which my pencil sharpener may be normally carried, provision being made for holding a 70 rubber eraser tip 11 in one end of the casing. The casing 10 is designed for protecting the pencil sharpener, and for forming a convenient covering so that the sharpener may be carried in the pocket. A lip or the like 75 10^a is adapted to enter longitudinal slot 18 in the sharpener body to prevent rotation of the sharpener in the casing.

My pencil sharpener includes fundamentally a hollow cylindrical body 15 having a 80 tapered or conical end portion 16, the cutting edges being formed on opposite sides of a longitudinal slot 18 which extends throughout the length of the body. In the tapered or conical portion of the body this 85 slot 18 is widened as at 18^a, and the opposite edges of the slot are formed into the cutting edges as illustrated. One of the chief peculiarities of my invention resides in the peculiar placement and formation of these 90 cutting edges. The cutting edges are preferably formed by grinding or otherwise forming a series of flat surfaces across the face of the enlarged longitudinal slot 18^a, these flat surfaces being designated by the 95 numerals 19, 20, 21 and 22. There may be as many cutting edges as desired; in the present case I have shown four. The cutting edges 19^a, 20^a, 21^a and 22^a are formed at the edges of the ground or otherwise 100 formed surfaces 19, 20, 21 and 22; and the peculiar juxtaposition and relative arrangement of the cutting edges is best illustrated in Figs. 1, 8 and 9. It will be seen that the ground surfaces 19, 20, 21 and 22 are arranged in different planes, each at an angle to the longitudinal axis of the body, so that the heel point 23 of each of the cutting edges is below the nose 24 of each of the adjacent cutting edges. This is most clearly 105 shown in Figs. 8 and 9. Between each cutting edge and the adjacent cutting edge, the 110

metal of the body is slit as at 25 so that the points 23 and 24 of adjacent cutting edges may be arranged as is best shown in Fig. 9. These slits 25 are made diagonally, so that 5 the nose 24 of each cutting edge will overhang the heel point 23 of the adjacent cutting edge both longitudinally and transversely; with the effect that, at the points represented by the section of Fig. 9, there 10 are two cutting edges operative upon the same portion of the pencil. In Fig. 9 a pencil is represented in dotted lines at 30; and it will be seen how both points 23 and 24 of adjacent cutting edges operate upon 15 the same section of the pencil. The points 23 and 24 are preferably arranged at the same distance from the center about which the pencil is rotated; that is, they are arranged to be on the true circumference of 20 the un-cut cross section of the pencil at that point in the sharpener. (In Fig. 9 the space between the pencil 30 and the bearing surface 50 is greatly exaggerated. In practice the pencil will bear against the surface 50, 25 being thus supported against the cutting edges opposite.) The effect of this arrangement is that each end point or portion of each cutting edge obliterates the mark on the pencil which otherwise would be made 30 by another end portion of an adjacent cutting edge. The cutting edges may be made in any configuration desired; in the present construction, I form the cutting edges so that the point of the pencil will be a true 35 cone when finished. It is seen from the drawings that each cutting edge is placed at an angle to a plane determined by the longitudinal axis of the sharpener body and by any point in the cutting edge. The cutting 40 edges do not coincide with elements of the conical point of the pencil but cross those elements at a suitable angle, so as to obtain the shearing effect herein described. This shearing cut operates to enable clean 45 sharpening of the pencil with a minimum force applied. The pencil may be rotated in either direction and cutting effected by either set of cutters. One set of cutters is cutting the pencil while the other set is 50 being sharpened by the abrasive action of the pencil rotating beneath the cutting edges.

It is designed that the cutting edges 19^a, 55 20^a, 21^a and 22^a cut only the wooden casing of the pencil, and do not cut the lead of the pencil. In this manner I may sharpen the wooden casing of the pencil back as far as desired from the point of the lead and may 60 afterward sharpen the lead to suit. When a pencil is inserted in my sharpener and rotated therein, or the sharpener rotated around the pencil, the lead will project through the central end opening 31 and will not be cut by any of the cutting edges. The wood may be sharpened back from the point

of the lead as far as desired. The lead may afterward be sharpened by and rotating in the end portion 32 of the sharpener, the lead being cut by the cutting edges 33 which are arranged as shown. The action of these lead 70 cutting edges is somewhat similar to the action of the wood cutting edges. Or the lead may be sharpened on the abrasive surface 34 on the exterior of the sharpener.

I have said that the body of the sharpener is substantially cylindrical in form, and this is generally true. But I provide means for allowing the compression of the body about a pencil which may be slightly smaller than the inner diameter of the sharpener. 75 The reduced neck portion 35 forms a guide for the pencil inserted in the sharpener. The longitudinal slot 18 throughout the body of the sharpener provides means for allowing contraction of the sharpener about a pencil. 80 I also provide short slits 36 in the body for the same purpose. In the portion of the body opposite the longitudinal slit 18 I also longitudinally slit the body as at 40, leaving only the bridges or webs 41 across the slit 90 40. This construction provides a section of weakened strength, and the whole body being made of resilient and elastic material, the webs 41 act as springs which resiliently yield to compression of the sharpener body about a pencil. In order to efficiently sharpen a pencil it is necessary that the pencil be accurately guided; and this provision for easily compressing the sharpener body about the pencil provides just such an accurate guide as is needed. With such an accurate guide and with the cutting edges arranged as herein described, I am enabled to quickly and efficiently sharpen a pencil 100 without any breakage of leads, and to cut 105 a smooth and even conical surface. The cutting edges being short in longitudinal extent are adapted to take hold on the wood of the pencil without excessive longitudinal pressure of the pencil into the sharpener; and each of the cutting edges cuts a clean smooth shaving from the pencil. The cutting edges may be very easily sharpened by simply running an oil stone or other sharpening implement across the faces 19, 20, 21 and 22, 110 115 such implement having preferably a sharp edge to reach in under the overhanging points 24. The lead cutting edges may be sharpened in the same manner. It is one of the features of my invention that the cutters may be very easily sharpened without removal from the body of the sharpener and without the use of any special sharpening device. The principal feature of my invention is the diagonal shearing placement of 120 125 the cutting edges. The division of the cutters into a plurality of sections facilitates this diagonal shearing arrangement; the overlapping of the end edges of the cutters causes the pencil to be sharpened into a uni- 130

form shape. The other features herein described complete my combination, producing a sharpener including all the features necessary for efficient use.

5 I claim—

1. A pencil sharpener, comprising a hollow cylindrical body having a hollow tapered end portion, the whole body having a longitudinal slit through one of its walls from 10 end to end and a spring portion formed in the opposite portion of the body wall so that the body may be resiliently compressed about a pencil, and a plurality of knife edges formed on opposite edges of said longitudinal slit in the tapered portion of the body, the edges on each side of the slit being juxtaposed end to end.
2. A pencil sharpener, comprising a hollow cylindrical body having a hollow tapered end portion, the whole body having a longitudinal slit through one of its walls, from 20 end to end and a spring portion formed in the opposite portion of the body wall so that the body may be resiliently compressed about a pencil, and a plurality of knife edges formed on opposite edges of said longitudinal slit in the tapered portion of the body, the edges on each side of the slit being juxtaposed end to end with one end of each cutting edge overhanging the adjacent end of the adjoining cutting edge.
3. A pencil sharpener, comprising a hollow cylindrical body having a hollow tapered end portion, the whole body having a longitudinal slit through one of its walls, from 30 end to end and a spring portion formed in the opposite portion of the body wall so that the body may be resiliently compressed about a pencil, and a plurality of knife edges formed on opposite edges of said longitudinal slit in the tapered portion of the body, each cutting edge being diagonal to a plane determined by the longitudinal axis of the body and by any point in the edge, so that 40 each edge is in position to effect a shearing cut on a pencil, the edges of each side of the slit being juxtaposed end to end with one

end of each cutting edge overhanging the adjacent end of the adjoining cutting edge.

4. In a pencil sharpener, a hollow cylindrical body having a longitudinal cutting edge, said cutting edge being formed of a plurality of individual cutting edges arranged substantially longitudinally end to end and formed directly on the body, the individual cutting edges being separated by transverse slits and one end of each individual edge overhanging the adjacent end of the adjacent edge. 50

5. In a pencil sharpener, a hollow cylindrical body with a hollow conical portion, the conical portion having a longitudinal slit with a cutting edge on one side thereof, said cutting edge being formed directly on the body and comprising a plurality of individual cutting edges arranged substantially longitudinally end to end, each cutting edge being slightly diagonal to the longitudinal axis of the body, and the cutting edges being separated by transverse slits in 60 the body making an acute angle with the individual cutting edges at their ends toward the larger end of the conical body portion. 65

6. In pencil sharpeners, a cutter comprising a single piece of metal with a plurality of cutting edges formed thereon, the cutting edges being arranged substantially longitudinally end to end and each edge being slightly diagonal to the longitudinal line of the set of cutting edges, the edges being 70 separated by transverse slits in the metal which slits make acute angles with one end of each cutting edge forming an acute angled corner, and said acute angled corners of the respective edges overhanging the adjacent 75 ends of the adjacent edges, substantially as described. 80

In witness that I claim the foregoing I have hereunto subscribed my name this 15th day of December 1913.

HENRY LA CASSE.
